PORATION OF PENNSYLVANIA

INDUCTION FURNACE

Application filed September 9, 1927, Serial No. 218,403, and in Great Britain November 3, 1926.

Our invention relates to furnaces and more particularly to electric furnaces of the induction type.

In electrical induction furnaces of the coreless type, employing, in general, a helically wound inductor coil surrounding a metallic charge to be melted, it is necessary to energize the coil at a relatively high current density which results in a considerable amount of heat being developed in the coil. To obviate this condition, it is necessary to resort to artificial cooling of the coil to prevent undesirable effects thereupon.

The usual expedient has been to form the coil of flattened tubing and to circulate a cooling fluid therethrough. The objection to such a construction is that the convolutions of the coil must be relatively large in cross-section to permit the passage therethrough of sufficient fluid to effect the desired cooling thereof, and to provide sufficient metal to carry the relatively large electrical current necessary to effect the melting of the charge.

It is an object of our invention, therefore, to provide in an induction furnace, a solid inductor coil and means formed upon a peripheral edge of the convolutions of the coil to effect the cooling thereof.

In practicing our invention, we provide, in conjunction with a crucible for containing the metal to be melted, a substantially helically-wound inductor coil surrounding the crucible, and means secured to the outer periphery of the coil convolutions for effecting the cooling thereof.

In the drawings,

Figure 1 is a vertical sectional view of an induction furnace embodying our invention, Fig. 2 is a vertical sectional view of a convolution of the inductor coil shown in Fig. 1,

Figs. 3 and 4 are vertical sectional views of modified forms of inductor coils.

Referring more particularly to Fig. 1, the furnace embodying our invention comprises a casing 2 of suitable heat-insulating material; a helically wound inductor coil 4 disposed therein and coaxial therewith, and a crucible 6 surrounded by said coil and adapted to contain the material to be melted. An

edge-wound ribbon 8, preferably mica, is disposed between adjacent convolutions of the inductor to provide the necessary electrical insulating therebetween.

As hereinafter more fully described, a conduit affording a passage for a cooling fluid is secured to a peripheral edge of the coil, extending substantially the entire length thereof, and projects through the casing 2 for connection with a suitable fluid supply (not shown).

The space between the casing, coil and crucible is filled with a suitable refractory electrically insulating material, such as zirconium silicate.

An annular plate 10 of refractory material is supported upon the upper peripheral faces of the casing 2 and crucible 6 to close the space therebetween occupied by the inductor.

The discharge of molten material from the crucible is facilitated by a passage formed through the plate 10 communicating with the crucible and terminating in a pouring spout 12 formed on the outer periphery of the casing 2.

A suitable cover 14, supported upon the plate 10, is adapted to be removed to permit the charging of material to be melted into the furnace.

Since the particular form and construction of the furnace forms no part of the present invention, a more detailed description thereof is not deemed necessary.

In the preferred form, shown in detail in Fig. 2, the coil comprises a solid electrically conducting portion 20, rectangular in cross section, which is grooved along a peripheral edge thereof to receive a tube 22 constituting a conduit for a suitable cooling fluid. The tube 22 is soldered or brazed in any well known manner to the conducting portion 20 in close interfitting relation.

In the modified form shown in Fig. 3, the same general construction is used but in this instance the fluid conduit is rectangular in cross-section and is coextensive in thickness with the lateral dimension of the solid conducting portion.

In Fig. 4, the peripheral edge of the con-

ducting portion 20 is grooved to form a relatively deep channel, and a flat strip 24 is soldered or brazed to the periphery thereof to form a passage for the cooling fluid.

5 In all the forms illustrated, the cooling fluid conduit is in close thermal relation with respect to the solid current carrying portion of the coil, so that heat generated in the coil is conducted to the fluid and carried off thereby.

10 When an alternating current flows through a conductor, the current density across a section of the conductor is not uniform. In cases where the conductor is coiled in the form of a helix, surrounding the charge to be melted, alternating current passing therethrough, especially at relatively high frequencies, is confined almost entirely to that side of conductor which is nearest the axis 15 of the coil. On the other hand, if the charge to be melted is located outside and around the inductor, the current density will be greatest in the portion of the inductor winding remote from the axis of the coil.

20 25 By the present invention, we have provided a cooling fluid conduit secured to the winding of an inductor coil remote from the axis of the coil which, in the present instance, is the point of lowest current density.

30 35 Quite obviously, the form of furnace shown, and the particular form of inductor coil are illustrative only and may be changed considerably without departing from the scope of the invention. For example, if the furnace is designed so that the charge surrounds the inductor the cooling fluid conduit will be secured to the inner periphery of the coil convolutions.

40 Various modifications may be made in our invention without departing from the spirit and scope thereof, and we desire therefore that only such limitations shall be placed thereon as are imposed by the prior art and set forth in the appended claims.

45 We claim as our invention:

1. In a coreless electric-induction furnace, a solid inductor coil adapted to surround the charge, to be melted, and means secured to said coil for effecting the artificial cooling thereof, said means comprising a metallic conduit, coextensive in length with a periphery of said coil.

50 2. In an induction furnace, an inductor coil comprising a solid helically wound conductor, and means for cooling said conductor comprising a conduit coextensive in length with the outer periphery of said conductor and secured thereto in heat-exchanging relation.

60 65 3. An induction coil comprising a conductor rectangular in cross section having a groove in a periphery thereof, and means associated with said groove, said means acting to restrain a flow of cooling medium to the periphery of said conductor.

4. In an electric inductor furnace, an inductor characterized by a radially inner solid electrically-conducting portion and a hollow projecting outer cooling portion adapted to receive a cooling liquid.

70 5. In an electric furnace, an edge-wound inductor of solid material and a water-cooled coil outside of the inductor and having heat-conductive connection with the inductor.

75 6. In an electric furnace, a primary winding, insulation between the conductors of the winding forming with the winding a protective shell and water-cooling for the winding located on the outer side of the winding and thermally connected with it.

80 In testimony whereof, we have hereunto subscribed our names this 24th day of August, 1927.
